UNITED STATES PATENT OFFICE.

DANIEL J. DE GRASSE, OF NEW YORK, N. Y.

AUTOMATIC WINDOW VENTILATOR.

Application filed March 19, 1927. Serial No. 176,736.

This invention relates to ventilators and has for an object to provide an automatically actuated ventilator designed to be used with double hung windows for the purpose of allowing fresh air to enter a room while preventing rain or snow from entering.

Another object of the invention is to provide an automatically shifted ventilator which acts to deflect the air upwardly into a room and thereby prevent a direct draught from the window across the room.

A further object, more specifically, is to provide a sliding and swinging ventilator for double hung windows with means co-acting with the window and frame whereby when the window is raised the ventilator is permitted to swing so that the lower edge will be beneath the window sash.

In the accompanying drawing—
20 Figure 1 is a fragmentary vertical sectional view through a window and a ventilator disclosing an embodiment of the invention.

Figure 2 shows the window sash and ventilator when in a partly closed condition.

Figure 3 is a sectional view through Figure 1, approximately on line 3—3.

Referring to the accompanying drawing by numerals, 1 indicates the window structure as a whole, said window structure being provided with what may be termed an inside sill 2 and an outside sill 3 offset from the sill 2 so as to form a shoulder or abutment 4. A sash 5 is mounted to slide on suitable runways 6 and to move downwardly and fit against the sill 3 as well as against the shoulder 4 when the sash is closed. The structure just described is old and well known and, therefore, forms no part of the present invention but is described and illustrated to disclose how the ventilator 7 may function. This ventilator is provided with a plate 8 on each side of the window as illustrated in Figure 3, said plates being identical except that the parts are made right and left. In view of this fact the description of one will apply to both.

As indicated in Figure 1, plate 8 is provided with a right angle slot 9 having legs 50 10 and 11, leg 10 being normally horizontal and leg 11 normally vertical. A screw 12 extends through slot 9 and when the ventilator is in full functioning position, will occupy the upper part of leg 11 and when in non-functioning position, will occupy one end of leg 10. The screw 12 is screwed

into part of the window frame of window 1 with the head overlapping part of plate 8 so that the screw 12 assists in controlling the up and down and swinging movement 60 of plate 8. This plate is also provided with a slot 13 which accommodates the screw 14, said screw also pivotally supporting the link 15. There is ample loose motion to permit plate 8 and associated parts to drop down 65 by gravity whenever permitted. Link 15 at the lower end is pivotally connected at 16 to the trigger or lever 17, said trigger or lever being pivotally connected at 18 to plate 8. The trigger 17 is substantially U-shaped 70 in cross section at the outer part thereof and straddles the flange 19 when the parts have reached the position shown in Figure 2.

By reason of this structure, when the sash 5 is moved completely down against the sill 75 3, the sash will press against the trigger 17 and swing the trigger 17, flange 19, plate 8 and associated parts to the dotted position shown in Figure 2. The plate 8 is provided with a flange 20 against which the 80 glass panel 21 rests. This flange at the lower end is turned up for forming a socket 22 designed to receive the lower edge of the panel 21 and support the panel. At the upper end the plate 8 is provided with a 85 pivotally mounted member 23 having a depending flange 24 formed with a bent ear 25 adapted to press against the upper part of the glass panel 21 for holding the same against the flange 20. By swinging the 90 member 23 upwardly as shown in dotted lines in Figure 1, the glass panel 21 may be readily removed at any time and replaced.

When the parts are mounted in position and the window is closed, the ventilator 95 structure will assume the position shown in dotted lines in Figure 2. As the window is raised, the lower part of the sash will move away from the trigger 17 and, consequently, the plate 8 and associated parts will swing 100 on screw 14 until it assumes the position shown in Figure 2. A further upward movement of the sash 5, as for instance, a movement which will bring the sash to the position shown in Figure 1, will cause a 105 complete release of trigger 17 and associated parts whereby they will swing on screw 14 and also move downwardly guided by both of the screws 12 and 14. This additional swinging movement from the position shown 110 in Figure 2 and the downward movement, will result in the lower edge of the glass

panel 21 moving below the upper edge of the shoulder 4. This will positively prevent the entrance of rain or snow while permitting the free entrance of air, which air is deflected upwardly. The respective plates 8 and associated parts move freely and automatically as the sash 5 is moved upwardly and downwardly. When the sash is moved from the position shown in Figure 1 upwardly, the ventilator will not move and in fact, will not move until the sash is moved down sufficiently to engage the trigger 17 whereupon a further downward movement will begin to raise the ventilator and then swing the same inwardly. On opening the window, the first few inches of raising of the sash 5 will permit the ventilator to automatically, and under the action of gravity, move downwardly and swing to the position shown in Figure 1 so that the window is still closed as far as rain and snow are concerned but is open for the passage of air in an upward direction. It will be noted that the plates 8 act as hangers as well as plates whereby air cannot pass the ends of the ventilator and also whereby the ventilator is properly suspended for up and down and swinging movement as described.

What I claim is:

30. 1. A ventilator for a double hung window, comprising end plates acting as hangers, a deflecting member connecting said end plates, means for slidably and pivotally supporting said end plates, and means operated by the window sash for raising said end plates and swinging the same out of the way when the sash is closed, said means acting to cause the ventilator to move downwardly and swing outwardly when the window is opened, said means including a link pivotally connected to the upper part of each of said end plates, and a sash operated trigger pivotally connected to each of said end plates near the lower part thereof, 45 and means for pivotally connecting the lower ends of the respective links to the respective triggers.

50. 2. A ventilator for windows, comprising a pair of vertically movable and swingable plates, lever mechanism including a pivotally mounted trigger actuated by the window sash for moving said swingable plates upwardly and then swinging the same out of the way of the window sash, said plates being moved by gravity downwardly and in the opposite direction, and a panel connecting said plates for deflecting air upwardly.

55. 3. A window ventilator, comprising a

deflecting plate, a pair of hangers for supporting said plate, means for swingably and slidably supporting said hangers, said means for causing the hangers to swing so that the lower edge of said plate will move outwardly and then downwardly below the outer window sill, and lever mechanism including a pivotally mounted trigger actuated by the window sash for moving said hangers upwardly and then swinging the same out of the way of the window sash. 60 65 70

4. A ventilator, comprising a pair of swinging and vertically slidable plates, each plate having a pair of slots, one slot being normally vertical and the other slot being formed with legs at right angles, one leg 75 being vertical and the other horizontal, a supporting pin extending through each of said slots for limiting the vertical sliding movement of the plates and also limiting the swinging movement thereof, a panel carried by said plates for deflecting the air, said plates and panel being movable downwardly under the action of gravity and then swingable in one direction under the action of gravity, and a lever mechanism including 80 85 a trigger operated by a window sash for raising said plates and associated parts and then swinging the same in the opposite direction to the gravity swinging movement.

5. In an automatically actuated ventilator, a pair of end plates, each plate being provided with an L-shaped slot in the center, a vertically positioned slot near the top and an arc-shaped slot near the bottom, a screw for each of the first two named slots 95 for swingably and slidably mounting the plates, a link pivotally mounted on the screw passing through the vertical slot, a trigger pivotally mounted on each plate near the lower end, and a pin carried by 100 said trigger extending through the lower end of said link and through said arc-shaped slot.

6. In an automatic window ventilator, a pair of side plates, a connecting panel, means for mounting the side plates so as to permit an up and down and swinging movement and a lever mechanism for moving the plates upwardly and swinging the plates in one direction, said lever structure including 105 a link pivotally connected with each plate near the top, a trigger pivotally connected with each plate near the bottom, and a pivotal connection between the link and trigger, said pivotal connection extending 110 through an arc-shaped slot in the plate. 115
